VERTICAL FILE RACK

Sven-Eric Juhlin, Gustavsberg, Sweden, assignor to AB Gustavsbergs Fabriker

Filed Mar. 7, 1972, Ser. No. 232,658

Claims priority, application Sweden Sept. 8, 1971

Term of patent 14 years

Int. Cl. D19—02

U.S. Cl. D74—2 A

FIG. 1 is a perspective view of a vertical file rack, showing my new design;

FIG. 2 is an end elevational view;

FIG. 3 is a top plan view;

FIG. 4 is a rear elevational view; and

FIG. 5 is a bottom plan view.

I claim:

The ornamental design for a vertical file rack, as shown.
